UNITED STATES PATENT OFFICE.

ERNEST PARKER HOWE, OF CLINTON, MASSACHUSETTS.

DESIGN FOR AN OVEN TURN-TABLE.

53,710.

Specification for Design.

Patented Aug. 19, 1919.

Application filed July 6, 1918. Serial No. 243,724. Term of patent 7 years.

To all whom it may concern:

Be it known that I, ERNEST PARKER HOWE, a citizen of the United States, residing at Clinton, in the county of Worcester and State of Massachusetts, have invented a new, original, and ornamental Design for Oven Turn-Tables, of which the following is a specification, reference being had to the accompanying drawing, forming a part thereof.

The figure is a plan view of an oven turn table, showing my new design.

I claim:

The ornamental design for an oven turn table, as shown.

ERNEST PARKER HOWE.

Witnesses:

LYMAN CAYERS,
FOSTER H. KINNEAR.
